[57] **CLAIM**

The ornamental design for a desk clock, as shown and described.

DESCRIPTION

FIG. 1 is a front view of a desk clock showing my new design;

FIG. 2 is a rear elevation view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken line showing of a support base is for illustrative purposes only and forms no part of the claimed design.
